US00D474149S

(12) **United States Design Patent** (10) Patent No.: **US D474,149 S**
Kawahata et al. (45) Date of Patent: ** **May 6, 2003**

(54) **STORAGE BATTERY**

(75) Inventors: **Nobuya Kawahata**, Yokosuka (JP);
Kazuya Umeyama, Edogawa-Ku (JP);
Hidefumi Ota, Kawasaki (JP)

(73) Assignee: **Nikon Corporation**, Tokyo (JP)

(**) Term: **14 Years**

(21) Appl. No.: **29/163,426**

(22) Filed: **Jul. 5, 2002**

(30) **Foreign Application Priority Data**

Feb. 13, 2002 (JP) 2002-003403

CLAIM

The ornamental design for storage battery, as shown.

DESCRIPTION

FIG. 1 is a front perspective view of storage battery showing our new design;

FIG. 2 is a front elevation view thereof;

FIG. 3 is a top plan view thereof;

FIG. 4 is a right side view thereof;

FIG. 5 is a left side view thereof;

FIG. 6 is a rear elevation view thereof;

FIG. 7 is a bottom plan view thereof;

FIG. 8 is a view of a cross-sectional slice thereof taken along line 8—8 of FIG. 2; and,

FIG. 9 is a view of a cross-sectional slice thereof taken along line 9—8 of FIG. 2.
